CLAIM

I claim the ornamental design for a dumpster enclosure, as shown and described.

DESCRIPTION

FIG. 1 is a perspective view of a dumpster enclosure of the present invention;

FIG. 2 is a front elevation view of the dumpster enclosure of FIG. 1;

FIG. 3 is a front elevation view of the dumpster enclosure of FIG. 1;

FIG. 4 is a right side elevation view of the dumpster enclosure of FIG. 1, the left side elevation view being a mirror image thereof;

FIG. 5 is a top plan view of the dumpster enclosure of FIG. 1; and,

FIG. 6 is a bottom plan view of the dumpster enclosure of FIG. 1.

The broken line showing the support feet are for illustrative purpose only and form no part of the claimed design.
